(57) **CLAIM**

The ornamental design for a wick, as shown and described herein.

DESCRIPTION

FIG. 1 is a top isometric view of a wick of the present invention;

FIG. 2 is a front elevational view of the wick of FIG. 1, a rear elevational view being identical thereto;

FIG. 3 is an elevational view of a first side of the wick of FIG. 1, a second side of the wick opposite the first side being identical thereto;

FIG. 4 is a top elevational view of the wick of FIG. 1;

FIG. 5 is a bottom elevational view of the wick of FIG. 1; and, FIG. 6 is a front elevational view of the wick of FIG. 1 within a container.

The subject matter shown in the figures above in dashed lines forms no part of the claimed invention. Further, the bottom views form no part of the claimed invention.
